ADJUSTABLE COUPLING

John W. Browning and James B. Adams, Havre, Mont., assignors, by direct and mesne assignments, of sixty-six per cent to said Browning, twenty-six per cent to S. T. Nelson and Elsie K. Nelson, and six per cent to John D. Gillan, all of Havre, and two per cent to Edwin Obie and Ann Y. Obie, both of Bozeman, Mont.

Application September 27, 1946, Serial No. 699,830

2 Claims. (Cl. 64—7)

1

Our present invention relates to an improved adjustable coupling adapted for interchangeable use in turning nuts and bolts and equipped with angularly adjustable means which adapt the tool for use in places that are usually inaccessible to straightline wrenches. The primary object of the invention is the provision of a wrench of this type that is composed of a minimum number of parts that may be manufactured and assembled with facility; in which the parts are combined and arranged in compact manner so that adjustments may be made with facility and the tool handled with convenience; and to insure a reliable, durable, and effective tool of this type.

The invention consists essentially in certain novel combinations and arrangements of parts as will hereinafter be described, and more specifically set forth in the appended claims.

In the accompanying drawings we have illustrated one complete example of the physical embodiment of our ratchet wrench in which the parts are combined and arranged in accord with one mode we have devised for the practical application of the principles of our invention. It will, however, be understood that changes and alterations may be made in these exemplifying drawings, and mechanical structures, within the scope of our claims, without departing from the principles of our invention.

Figure 1 is a view in elevation of a ratchet wrench in which our invention is embodied, and showing the tool adjusted for operation at an angle.

Figure 2 is an enlarged longitudinal sectional view of the tool, in straight line position, and as at line 2—2 of Fig. 1.

Figure 3 is a view in elevation of the housing portion of the tool, with its cover plate removed, showing the two pawls, with one pawl in co-acting engagement with one of the ratchet teeth.

Figure 4 is an enlarged detail sectional view of the holder for the ball of the universal joint of the angularly adjustable tool.

Figure 5 is a transverse sectional view, at line 5—5 of Fig. 3.

Figure 6 is a perspective view of either of the two pawls of the ratchet mechanism, enlarged and detached from the wrench.

Figure 7 is a partial sectional view at the free end of the housing, showing a retractile lever mechanism for turning the wrench.

Figure 8 is an enlarged detail view partly in section showing the universal joint of the angularly adjustable tool.

2

In carrying out our invention we employ a solid cylindrical shaft 1 upon which is rigidly mounted a lower bearing head 2, a spaced round collar 3, and a spaced long gear 4 of the ratchet mechanism. One end of the shaft is journaled to turn in a socket 5 drilled in the solid end of a cylindrical tubular housing 6 that may be employed as a handle or hand grip for the tool.

In the lower open end of the tubular housing 6 10 the bearing head 2 is mounted, and between the head and the spaced collar 3 a split or sectional thrust bearing ring 7 is interposed and secured in place by means of screws 8, one of which screws is employed for fastening an inset cover plate 9 to 15 close a lateral opening in the tubular wall of the housing. The housing is thus rotatably mounted upon the shaft 1, and it may be turned, as indicated in Figs. 1 and 7, by means of a retractile lever A that is pivoted at B in the solid 20 end of the housing. The pivot end of the lever is fashioned with spaced notches C, C, for co-action with a spring pressed ball-detent D. In the drawings, the lever is shown in extended position for use in turning the housing, and the housing 25 is provided with an exterior groove E into which the lever may be folded or retracted when not required for use.

Especially for heavy duty under varying conditions, the housing may be turned by means of 30 a cross bar (not shown) passed through a transverse cylindrical bore 10 drilled in the solid end of the housing, or the housing may be turned by means of a crank-handle (not shown) applied to an angular socket 11 that is axially aligned 35 with the shaft of the tool.

Between the ratchet gear 4 and the cover plate 9 of the housing, two spring actuated pawls 16 and 17 are mounted, and manually controlled, in 40 adjusting the wrench for right-hand turns, and for left-hand or reverse turns of the housing, involving a forward and backward movement of the lever or crank without removing the wrench from a bolt or nut. The pawls 16 and 17, as shown in the drawings, may rigidly connect the 45 housing and shaft for a continuous one way turning movement of the wrench; and the pawls 16 and 17 may jointly be disconnected from the ratchet gear of the shaft.

For these operations the housing is provided 50 with a longitudinally extending slot 12, and two longitudinally spaced transverse or arcuate recesses 13 and 14 in its wall, and the walls of the recesses terminate in pairs of cam-faces or seats 15. These recesses provide spaces for the 55 reception and retention of the two reversely ar-

3

ranged and oppositely disposed pawls 16 and 17 that co-act with the teeth of the ratchet gear in transmitting movement from the housing to the shaft 1.

As indicated in the drawings the pawls 16 and 17 are each provided with a pivot member 18 that is transversely arranged to occupy a recess, as 13 and 14, and the pivot member of each element is fashioned with angular faces 19 and 20 that meet to form a rib 21 that is adapted to 10 serve as a pivotal bearing on the cam faces 15 of the recesses.

The positions of the pawls 16 and 17 are adjusted manually by use of push buttons 22 and 23 as best seen in Figures 1 and 2. Each of these buttons is equipped with a pin 24, projecting through and slidably in a slot of the cover plate 9, and a spring 25 mounted on the end of the pin within the opening of the housing. The springs are oppositely disposed, the upper one bearing against the member 18 of the pawl 17 and the lower one bearing against the member 18 of the pawl 16. In Figure 2, the pawl 17 is held in engagement with the ratchet gear, and the pawl 16 is held out of engagement from the ratchet gear. By an upward push on the buttons 22 and 23, the relative positions of the pawls 16 and 17 may be reversed as the pivot members 18 rock on their pivot edges 21; and by manipulation of the buttons both the pawl 16 and the pawl 17 may be engaged with the ratchet gear; or both of these elements may be disengaged from the ratchet gear.

Below the housing, a hand grip or handle, in the form of a cylindrical sleeve 26 of molded plastic material or other suitable material is loosely mounted upon the shaft 1 between the bearing head 2 and an annular shoulder of an integral enlarged shank 27 of the shaft 1. This shank, which is of tubular form, is provided with an integral, externally threaded boss 28 upon which a retaining chuck 29 is threaded, for holding the angularly adjustable and universally jointed socket head of the wrench.

The universal joint includes a spherical head or ball 30 which is retained within the chuck by an inner annular flange 31, and the ball is pivoted to swing in one plane on a pin 32 threaded through the chuck, through the spaces provided by opposed cavities 33 and 34 within the ball which merge at the center of the ball. The ball can swing about the pin 32 as an axis. Also, the ball can swing in the plane of the slot provided by the cavities 33 and 34, through an angle of about 90 degrees.

Within the chuck a hemi-spherical holder 35 for the ball is mounted, and the stem 36 of the holder projects upwardly into the tubular bore of the shank 27 of the shaft 1. The concavity or socket portion of the holder is fashioned with a series of arcuate grooves 36a with which a bead or lobe 37, in the nature of a key co-acts to lock the ball in adjusted relation within its holder.

The skirt of the chuck is fashioned with notch 29a and the skirt or circular edge of the holder is also provided with a notch 38 to accommodate a stud 40 that is integral with the head or ball 30, and notches 39 to accommodate the pin 32, in adjusting the working end of the wrench.

The stud 40 has a squared end 41 that is adapted to be inserted in one socket head 42 of an interchangeable series of socket heads or wrench jaws, and in Figure 2 a quick detachable spring pressed detent is indicated at F on the squared end for fastening the socket head on the stud.

4

For manual control in locking the flexibly jointed socket head in adjusted position, a partially rotatable pin 43 is mounted in the tubular shank 27 above the stem 36 of the holder, and a 5 transversely arranged push pin or handle 44 passes outwardly through a Z-shaped slot in the shank, indicated at 45 in Figure 1 to raise or elevate pin 43 against tension of a helical spring 46 and release the holder from the ball. In 10 "down" or depressed position of the cross pin 44, the spring engages and locks the holder with the ball.

If the head 30 is turned about the pin 32 as 15 an axis until the stud 40 is located in the slots 29a and 38, the head 30 can then be turned by the handle 26, which will extend at about a right angle to the stud 40. However, if the stud 40 is at an angle of less than 45 degrees with respect 20 to the handle 26 the head 30, the pin 32 and the retaining chuck 29 form a universal joint. Rotation of the handle 26 about its axis causes the pin 32 to turn the head 30 by pressing against the sides of the slots 33 and 34. The pin 32 rocks 25 in the slots 33 and 34, as the handle 26 is rotated, to take care of the difference in angular position of the pin with respect to the stud 40.

The angle between the handle 26 and the stud 30 40 can be maintained constant by locking the holder 35 down against the head 30 with the bead 37 seated in one of the grooves 36a. The bead 37, which is diametrically opposite to the stud 40, follows a circular path around the inner surface of the holder 35 when the handle 26 and the stud 40 are rotated about different axes intersecting at the center of the head 30. Thus, if the head 37 is held in one of the grooves 36a, the stud 40 will be maintained at the same angle to 40 the handle 26 as the handle rotates.

Having thus fully described our invention, what we claim as new and desire to secure by Letters Patent is:

1. In a wrench of the ratchet type, the combination with a shaft and means for turning the shaft, a tubular shank rigid with the shaft, and an enlarged boss rigid with the shank, of a cylindrical chuck threaded on the boss, a slotted ball pivotally mounted within the chuck and a socket-head carried by the ball, a hemispherical holder having interior grooves and mounted in the chuck, a bead on the ball for selected co-action with said grooves to lock the ball in angularly adjusted position, and a spring-pressed 45 detent mounted in the shank for co-action with the holder to unlock the ball from its holder.

2. In a ratchet wrench, the combination with a shaft, an enlarged chuck on the shaft, a ball pivotally mounted within the chuck and having a 50 stud projecting therefrom, the stud having a socket-head thereon, said chuck and ball having a pin and slot connection within the chuck permitting the ball to rock in a plane through the axis of the chuck, a holder in the chuck having a spherical seat for the ball, and coacting means on the holder and ball releasably maintaining the stud at a definite angle to the shaft, said means comprising grooves in the seat of said holder 55 and a bead on the ball.
